UNITED STATES PATENT OFFICE.

HENRY FORT FLOWERS, OF NEW YORK, N. Y.

DUMPING-CAR.

1,268,829.

Specification of Letters Patent. Patented June 11, 1918.

Application filed November 27, 1914. Serial No. 874,165.

To all whom it may concern:

Be it known that I, HENRY FORT FLOWERS, a citizen of the United States, and a resident of the city of New York, borough 5 of Manhattan, in the county and State of New York, have invented certain new and useful Improvements in Dumping-Cars, of which the following is a specification.

One of the objects of my invention is to 10 construct a dumping car having a body which is movable horizontally across the under-frame and which is then tilted so as to discharge the load.

Another object of the invention is to 15 design a car so that it will have a tilting body that will be maintained at a minimum height above the under-frame and track and which, at the same time, will be able to deposit its lading, when dumped, at a point sufficiently 20 distant from a track or roadway to enable other cars to pass along the same track without obstruction.

A further object of the invention is to 25 provide a car which will combine the advantages of a car having a side tilting body, which will be suitable for use as a general service car, and which car will permit dumping of the load between the tracks.

The invention involves an operating mechanism 30 for tilting a dumping body to either side, a dumping or tilting body that is provided with trap or bottom doors which are so constructed as not to interfere with the side tilting operations, and a design of under-frame that facilitates the employment 35 of this combination of bottom dumping and side tilting body.

The car which is the basis of this application is comparatively simple and inexpensive 40 to make, and one that requires only a relatively small amount of power for its operation.

The invention particularly relates to a 45 tilting body mounted on rollers that move horizontally on a track on the under-frame in such a manner that the body moves faster than and in the same direction as the rollers until the body starts to tilt, from which time the rollers and the body may move together 50 as one and the rollers serve as rockers. The centers of these rockers are located so that from the time the tilting of the body begins up to the time that the lading is being 55 actually discharged, the body may be easily retained in any desired position, and so that after the discharge of the lading the body

will automatically, or at least tend to automatically, resume its original horizontal position by force of gravity.

This invention also relates to a power 60 transmitting mechanism, comprising a flexible power transmitting member, for producing the horizontal and tilting motions of the body; and a mechanism whereby the doors may be automatically opened as the 65 body approaches its dumping position. This invention is also directed to a mechanism for operating the trap doors that may be provided in the bottom of the tilting body. The flexible power transmitter, preferably a 70 rope or chain, operates on a series of sheaves, at least two of which, of different diameters, are rigidly connected together so as to provide a differential gearing which accomplishes a great multiplication of the force 75 applied to at least one of the sheaves, or of any external force applied to the flexible power transmitting member.

The car is also provided with a door 80 catch or door gear mechanism which comprises an eccentric or toggle link constructed so as to accomplish four things:

First, to open simultaneously and automatically, when desired, all of the doors on the down or discharge side as the body tilts 85 and approaches the discharging position.

Second, to open any one or more catches without disturbing the others that are attached to the same shaft.

Third, to open all of the catches on one 90 side simultaneously with a hand lever at either end of the body, and

Fourth, to catch all of the doors and pull them up tight to the body by the operation 95 only of the last mentioned lever.

This construction permits the body to be divided into separate compartments having individual doors so that different kinds of material may be hauled at the same time, and dumped at different points.

Some of the advantages of my invention are that it affords the construction of a two-way dump-car that is particularly adaptable to railway service and that especially overcomes the difficulties of dumping the lading 105 clear of the track where the top of the rail is at grade level; and that it also provides a construction of car having a dumping body that will have side boards or doors close to the ground and hence make the loading 110 height a minimum.

The invention furthermore facilitates the

construction of a side dumping car having a tilting body that may be revolved through a large dumping angle for insuring a discharge of any material that has a tendency to stick in the body. The invention also permits a car to be realized which employs a tilting body which is so balanced that as soon as its load is discharged it will have a tendency to revolve back to its horizontal position without the application of any power other than that attained by virtue of the shifting of the center of gravity when the load is discharged. The invention enables the construction of a low self clearing side dumping car that is serviceable in mines where the overhead height is limited and where, at the same time, a large tilting angle sufficient to discharge the load is required, be the load wet loam or any of the materials that require more than a forty-five degree angle for dumping.

As showing a specific embodiment of the invention reference is made to the accompanying drawings forming a part of this specification, and in which drawings,

Fig. 1^a illustrates the body latch or locking mechanism. Fig. 1^b illustrates the manner of mounting a removable stop.

Fig. 2 is a transverse vertical sectional elevation of a part of the car and is a view taken on the line A—A, Fig. 3.

Fig. 2^a is a partial plan view showing the relation of the rollers that support the body, the stops that are on the body arranged to engage a portion of the rollers and a portion of the side members upon which the stops are mounted. In this figure one of the stops is shown partially broken away.

Fig. 3 is a side elevation of an end portion of the car.

Fig. 4 is a half longitudinal vertical sectional elevation of an end portion of the car. This is a view taken as on the line B—B, Fig. 1.

Fig. 4^a shows another form of roller construction for supporting the car body.

Fig. 5 is a plan of a platform at one end of the car, a part of the under-frame, and the floor of one compartment, showing in the bottom thereof one trap-door which is opened and one which is closed.

Fig. 6 is a sectional elevation, as along line C—C of Fig. 5, showing the rack and pinion and roller for operating the trap-door.

Fig. 7 is a sectional end elevation, as along line D—D of Fig. 5, showing the rack and pinion and roller of the door operating mechanism. In this figure there is also shown certain reinforcing beams for the floor plates.

Similar numbers and letters refer to similar parts throughout the specification and several views of the accompanying drawings.

The car comprises the trucks A, the under-frame B, the tilting body C and the mechanism D for operating the tilting body.

The body is provided with swinging side doors E and operating gearing or locking mechanism F therefor. The under-frame is constructed so that doors G can be placed in the bottom of the car whereby a discharge of the load on the ground between the tracks can be effected through the openings for said last mentioned doors, if desired.

The door locking mechanism F is constructed so that it can coöperate with the under-frame, see stop-member H on the latter, whereby as the tilting body approaches the extremity of its tilting position the swinging side doors E on the lower side of the body will be automatically unlocked.

The tilting body is supported on the under-frame B by means of the rollers K, and there is provided between said body and the under-frame mechanism comprising cleats L and ways M for insuring the stability of the body on the under-frame when the body is in load carrying position. The car is also provided with suitable body locking mechanism as N for positively retaining the body in central position when the car is in transit.

The trucks A may be of any suitable construction as long as they are adapted to carry the under-frame, body, and its load. They may also be of either the motor type or the non-motor type, dependent upon whether the car is to be self-propelled, or whether it is to be hauled by some other power.

The under-frame B preferably comprises a longitudinally extending main center sill construction 1 and two longitudinally extending side sills 2, that are positioned over the side bearings 3. The side sills are arranged as far as possible from the center sill so as to permit the load to be dumped between the center sill and the side sills through comparatively large openings such as are provided for the trap-doors G in the bottom of the body C. It will be observed, however, that the extreme outward position of the side sills is determined by the clearance required for the body when in tilted position, since there must be no interference with the movement of said body said side sills. The under-frame is also provided with the needle beams 4 and the body bolsters 5 which are rigidly secured to said sills whereby a rigid built-up structure is produced.

The bottom body C may have only a single compartment, but in the form shown

in the drawings it has several compartments which are separated by the transverse partitions 6, which may be utilized to provide pockets or receiving spaces 7 for some of the rollers K.

The rollers K rest upon the tracks 8 that are carried on or constitute a part of the under-frame. These rollers K roll along said tracks when the body C is being moved from load carrying position shown in full lines in Fig. 1 to the tilted position shown in dotted lines in said figure. The cars are provided with the angle iron track members, such as 9, and the lower flanges of the I-beams in the transverse partitions serve also as tracks, see 10. These tracks 9 and 10 rest upon the rollers K whereby the car body is properly supported.

By referring to Figs. 2 and 4 it will be noticed that the point CG representing the location of the center of gravity of the body when empty is below tracks 9 and 10, which are the lines of support of the tilting body.

From an inspection of Fig. 2 it will be observed that the rollers K are arranged in pairs and connected together by links 11. It will also furthermore be noted that the car body travels twice as far as the center line of the rollers until the body starts to tilt, from which time the rollers on the tilting side and the body move together, the body and rollers swinging together, as one, with the rollers acting as rockers. It will be observed that when the car body is near the end of its travel toward the side of the car the spindles 12 of the rollers which are nearest the side to which the load is to be dumped engages the stops 13 that are on the car body, to wit, upon the portions marked 13* of the car body. When this engagement takes place further relative horizontal movement between the rollers and the car body cannot take place and from then on the rollers which are at the side to which the load is to be dumped serve as rockers upon which the body swings from horizontal to inclined position. Since the stop 13 is arranged so that the spindles 12 can be practically in line with the vertical center line of the car the load is substantially balanced, whereby with a slight pressure this tilting of the body can take place. The roller spindles 12, however, are sufficiently away from the center of gravity whereby, when the load has been actually discharged, the body will easily be restored to horizontal position and in fact during the latter part of its movement toward horizontal position the body tends to automatically restore itself to said horizontal position where the body can be moved to its load carrying or central position by the body operating mechanism D. The center of gravity of the body is on the vertical center line and is approximately at the point marked CG in Fig. 2.

The rollers K have grooves or cut-out portions 14 that mesh with the teeth or heads 15 of the rivets that secure the tracks 8 to the under-frame. These groove portions 14 also mesh with teeth or rivet heads 16 which are provided on the tracks 9 and 10 that rest upon the rollers.

In Fig. 4 it will be seen that the tracks 8 on the under-frame are, in the middle portion of the car, in the form of channel-irons arranged with their flanges up-standing so that said flanges can serve as stops for receiving any longitudinal thrusts which are imparted thereto by means of the lower portions 17 on the car body engaging with said flanges. These flanges are designated as 'f', f', f'', etc. There is sufficient play, however, between the up-standing flanges and the portions 17 to permit a free lateral movement of the car body along said tracks or transversely of the under-frame.

The mechanism D for operating the tilting body comprises hand-wheels 18 fixed at each end of the longitudinal shaft 19 which extends the full length of the car body. This shaft is mounted so that it may freely revolve in a casing 20. In the construction shown this shaft and casing therefor is arranged along the longitudinal central portion of the car body, but this shaft and casing may be located at the side of the car, for instance along the upper hinged portion of the doors, if for any reason it becomes desirable to remove the shaft from the central portion of the car toward the side thereof. The shaft 19 could be located elsewhere, if desired, the principal function of this shaft being to cause the operating mechanism at the opposite ends of the car to act in unison. Double grooved sprocket sheaves 105 are rigidly fixed to opposite ends of the shaft 19 and these sprocket sheaves are of such a construction as to effect a positive drive on the chains 22, one of which chains is located at one end of the car and the other 110 of which is located at the other end of the car. As the construction at each end of the car is substantially the same a description of the mechanism employed at one end will suffice for both. The flexible member 22 is 115 preferably an endless chain which passes (see Figs. 1, 4 and 5) from the groove 23 of the double sheave 21 down to the vertical sheave 24; then to the left to the horizontal sheave 25 back to the right to the vertical sheave 26; thence up to the second groove 27 of the double sheave 21; thence down to the vertical sheave 28 to the right to the horizontal sheave 29, to the vertical sheave 30 and returning to the first groove 23 of 125 said double sheave 21.

The sheaves 24, 30, 26 and 28 are all idler sheaves and they are called vertical sheaves because they rotate in vertical planes. The shafting for these sheaves is supported by 130

the frame or bracket supported on the end of the car body. The sheaves 25 and 29 are all idler sheaves and they are called horizontal sheaves because they rotate in horizontal planes. These horizontal sheaves are rotatably mounted on the under-frame.

Due to the fact that the diameter of the groove 23 in the double grooved sprocket sheave 21 is larger than the groove 27 there will be produced a differential movement of the different portions of the chain gearing passing over said sheave 21 and, consequently, the vertical grooved idler sheaves will be pulled as a set either to the right or the left, dependent upon the direction in which the hand-wheel 18 is rotated. As this pulling operation proceeds it causes a lateral or transverse movement of the car body as a whole relative to the under-frame whereby the body can be forcibly moved from its central or load carrying position to either the right or left. When the body is in substantially the extreme right or left position, as the case may be, the car body stops by the proper set of roller spindles 12 and from then on the car body tilts around the proper set of rollers or spindles 12 as rockers, so as to dump the load in the desired position.

As before indicated, when the load or lading has been discharged from the car body the car body tends to automatically restore itself to horizontal position and it can be assisted in this movement, if desired, by the endless chain gearing mechanism just referred to. To insure the stability of the car body cleats L are provided on the under-frame near the sides thereof, and these cleats coöperate with ways or flanges M on the car body, when the latter is in central position. The ways and cleats are arranged so that disengagement can take place prior to the body starting to tilt.

The under-frame also has pivotally mounted thereupon a latch of the locking mechanism N, which latch is arranged to engage the car body or some member thereupon, such as the bracket or frame for supporting the shafting of the four idler vertical sheaves, for positively retaining the car body in its central position on the under-frame.

Specifically the locking mechanism N comprises a double locking bar 50, to wit the latch above referred to, that is pivotally mounted at 51 upon the main center sill 1 by means of a pin 52. The spaced ends 53 and 54 of the locking bar are located upon opposite sides of a projecting member 55 that extends from an end of the tilting body.

There is a locking mechanism at each end of the car.

As previously stated the car body is provided with swinging doors E. There is a swinging door at each end of each compartment provided in the car body and these

doors are secured in place by the hinges 31 whose pivotal points are located along the upper edge of the car body as at 32. These doors E are mounted so that they can be secured in position by the catches 33 whose operation will hereinafter be described more in detail, but so that they can swing to the position shown at the lower right hand end of Fig. 2. These doors are furthermore constructed so that when the catch 33 is raised from the full line to the dotted line position shown at the left hand end of Fig. 2 the door can be swung from the full line position to the dotted line position shown at the left hand end of said figure, whereby the car can be loaded by material thrown in the car body from below the door, should such a method of loading be desired. In order to provide a receiving space which will permit a sufficient movement of the catch from its door holding position to a position where the door will be free to swing, openings 34 are provided through which the catches pass.

Longitudinally extending door latch gear operating shafts 35 are provided along each side of the car. These shafts are located below the floor bottom of the car body and each shaft has thereupon several sets of crank arms 36 to which are pivotally connected at the free ends the several door catches 33. The shafts 35 are also provided with other crank arms 37 which constitute a part of the mechanisms between the shafts and the under-frame whereby the desired shaft 35 (or shafts should there be more than one at each side of the car) will be caused to partially rotate as the body approaches its full tilted position. Slotted levers 38 are carried on pivot pins 39 that are secured to the car body. One end of each of these slotted levers 38 is directly connected to a crank arm 37 and another portion of the lever 38 is arranged so that as the body assumes the full tilted position just referred to said lever will engage the stop H that is on the under-frame. It will thus be observed from an inspection of Fig. 1 that as the right hand end of the car body lowers the upper or free end of the lever 38 will press against the stop, turning about the pivot 39 as a fulcrum, and thus cause the free end of the arm 37 to move so as to partially rotate the shaft 35 which carries said arm. The partial rotation of this shaft causes the lower free ends of the crank arms 36 to move downwardly and this downward movement of the free end of the crank arm 36 causes the lifting of the free end of the catches 33 which are on the discharge side of the car, since said catches will rest upon the shaft 35, or the hub portion of the crank arms 36, as a fulcrum point, and will thus turn with the shaft.

The shafts 35 are also provided with shaft operating handles 40 for manually releasing

the catches when desired, either when the car body is partially tilted, or when it is in a horizontal position.

From an inspection of Fig. 2 it will be noted that there is nothing above the catches 33 for preventing any one or more of them being moved upwardly independent of the others. This is of considerable advantage where it is desired to open only one or a few of the swinging doors; as, for instance, when only a portion of the load is to be dumped. The door-catch-crank-arms 36 just referred to are of considerable advantage in the locking of the swinging doors E in their closed position, because by the swinging of the handle 40 from the position Y to the position Z the crank arm 36 moves the catch so that the door engaging portion thereof will move outwardly a substantial distance beyond the position it occupies when holding the door in closed position, thus enabling the catch 33 to properly engage the door by gravity should the latter be a substantial distance away from its final closed position, due to any gravel or other obstruction which may possibly cause it to stick. When the handle 40 is forced from the position Z back to the position Y it will cause the catch 33, due to the crank arm 36 being moved, to pull the door to its final closed position where the crank arm holds and locks the catch in position, due to the toggle link construction employed.

Cars of the class under consideration are frequently used to carry ladings of different character; for instance, stone in one compartment, cement in another, and sand in another, and it frequently is desirous to discharge only one compartment and allow the rest of the compartments to retain their ladings. Such a discharge is permitted, due to the construction just referred to.

As it is not always desirable to have all of the doors dump automatically, the stop H can be made removable, as by making the stop construction to comprise a removable bar which is inserted through an opening in the under-frame. Such a construction is illustrated in the drawings in Fig. 1^a, in which the stop H appears as a shouldered bar that slides in the socket provided by the member 56.

It is often desirable to have a car constructed so that it will empty a part of the load to one side, but at a comparatively remote distance from the track, and to empty another part of the load directly upon the tracks. To permit the latter to take place I have provided the compartments with trap-doors. These trap-doors are indicated by the reference character G and two are shown for each compartment. These trap-doors are arranged so that when they are removed from door closing position the load can pass downward through the space be-

tween the center sill 1 and the side sills 2. In Figs. 5, 6 and 7 the operating gears for these doors are clearly shown. As very little space is permitted for the trap-doors and this operating mechanism between the bottom of the car and the top of the under-frame the doors are made so as to slide horizontally, and they rest upon the rollers 41 whose movement is one-half of the total movement of the car doors that they support. The position of the rollers 41, when the door is open, is indicated at X. In Fig. 5 the doors are each provided with racks 42 that are engaged by the pinions 43 which are on the hand operated shafts 44.

It will thus be manifest that the car herein described is a side dumping car of the tilting type, that is also applicable for general service conditions, and that it is provided with doors which permit a discharge of the load past or through the under-frame directly upon the ground between the tracks.

It should be noted that the car construction is such that when the load is placed far enough to one side of the car to cause an over-balancing of the body before the stops 13 engage the spindles 12 the body may begin to tilt as soon as one end of each of the flanges M (see Figs. 1, 4 and 5) clears or disengages the cleats L that retain the body in horizontal position on the under-frame. Hence, the body may be tilted without utilizing the function of the stops 13, provided the body is permitted to do so by the body operating mechanism D, which mechanism may be utilized as a means for preventing a complete tilting of the body when the latter starts to tilt under the conditions just referred to.

The rollers K may have peripheries, for instance, two of different lengths or diameters, and the body may rest upon one of these peripheral portions while another peripheral portion of the roller rests upon the under-frame. Such a construction is shown in Fig. 4^a. In this figure the under-frame track-bar is designated by 57 and the larger peripheral portions 58—58 of the roller rest upon the under-frame track-bar 57. A body track-bar 59 rests upon the smaller peripheral portion 60—the portion of the roller having the smaller diameter. The limiting diameter of the larger one of these peripheral portions is the extreme external diameter of the roller; the limiting diameter of the smaller peripheral portion is a small journal near the center of the roller. According to all constructions, however, of that phase of the invention which is related to the supporting of the car body on bodily movable rollers, the rollers will move in the same direction as the car body moves when the latter is being transferred from its central load carrying position toward the side of the car.

In the case of simple rollers, such as rollers K shown in the drawings, the two peripheral portions just referred to coalesce, and in such case the roller has but one peripheral portion which rests upon the under-frame, and upon the same peripheral portion the car body rests. With such simple rollers the body moves a distance equal to twice the distance traversed by the axes of the rollers.

10 The car body is provided with pockets or receiving spaces for rollers or rockers and the receiving spaces are of sufficient depth and the body is constructed so that the center of gravity of the latter, when empty, will be below the points where the body is supported on said rollers or rockers, whereby there is a strong tendency for the car body to rest in its horizontal position when 15 a series of said points of support are in alignment with the center of gravity.

A platform is provided at each end of the car upon which the workmen can stand in moving the car body from its horizontal 20 or central position to its tilted position and back again. This platform may also be used to place thereupon a cab for the motor-man, should the car be of the self-propelling type, such as is utilized on electric railways.

25 The invention is not confined to railway cars alone, but is applicable to any other vehicle or carrier adapted to convey and dump loads. Furthermore, the improvements herein set forth are not limited to the precise construction and arrangement shown and described as they may be embodied in various forms and modifications without departing from the spirit and scope of the invention.

30 I claim as my invention:

1. In a car or other vehicle of the class described, an under-frame, rollers thereon and arranged in pairs so that each pair can move transversely relative to the under-frame, a tilting body resting on said rollers, and mechanism carried by the car and cooperating with the underframe and body for shifting the body horizontally to either side until the body starts to tilt, which mechanism is constructed so that it can allow the body to tilt, the construction of the body and the rollers being such that when the body moves horizontally it travels faster than but in the same direction as the center lines of the rollers up to the time when the body starts to tilt, from which time the rollers on the side to which the body is tilted move with the body and serve as rockers.

2. A dumping car of the class described having a frame supported upon trucks, horizontal tracks mounted upon the under-frame and extending transversely thereof, body supporting rollers on said tracks, a body provided with tracks which rest upon supporting rollers, and differential gear

mechanism for moving the body transversely of the under-frame whereby the body can be tilted for the purpose of discharging the load away from the car tracks, the construction being such that the body travels faster but in the same direction as the rollers until the body starts to tilt, from which time the rollers on the tilting side of the car move with the body and serve as rockers.

3. A vehicle of the class described comprising a longitudinally extending under-frame having thereupon horizontally, transversely extending tracks, rollers on said tracks and movable along the same, a tilting body having track members which extend horizontally and transversely, when the body is in central or load carrying position, and which track members rest upon said rollers whereby the body is supported by means of the rollers, and mechanism for forcing said body transversely of the under frame until the body starts to tilt, at which time a part of said rollers serve as rockers upon and relative to which the body is revolved when being tilted.

4. A dumping car of the class described having an under-frame, rollers arranged in pairs mounted on the underframe so as to move transversely thereof, a car body supported on said rollers so that during horizontal transverse movement it will move a greater distance than the rollers move, and mechanism whereby the rollers along one side of the car can serve as rockers upon which the body tilts when it has been moved to one side of the under-frame, the construction of the car body and arrangement of the rollers being such that after the load has been discharged the center of gravity of the car body will be so positioned that there will be a tendency for the car body to restore itself to its horizontal position by gravity.

5. A dumping car of the class described having an under-frame, rollers arranged in pairs mounted on the under-frame so as to move transversely thereof, a car body supported on said rollers so that during a horizontal transverse movement it will move a greater distance than the rollers move, and stop mechanism between the body and the rollers whereby the rollers along one side of the car can serve as rockers upon which the body tilts; the construction of the car body and the arrangement of the rollers being such that after the load has been discharged the center of gravity of the car body will be so positioned that there will be a tendency for the car body to restore itself to its horizontal position by gravity.

6. A car having an under-frame, a body mounted thereupon so that it can be moved laterally in either direction from its central load carrying position to a tilting position, and mechanism for effecting said lateral movement, said mechanism comprising idler

sheaves carried on the under-frame, idler sheaves carried on the body, a differential sheave, and a flexible connector passing over all of said sheaves in such a manner that a 5 powerful pull can be exerted between the body and under-frame by the turning of the differential sheave.

7. In a dumping car a mechanism for effecting the lateral movement of a tilting body, which mechanism comprises at each 10 end of the tilting body, idler sheaves that are carried on the under-frame, idler sheaves that are carried on the body, a differential sheave, and a flexible connector passing over 15 all of said sheaves, the differential sheaves at the ends of the car being mechanically connected together.

8. In a car of the class described a tilting body mounted on an under-frame carried 20 by trucks, the tilting body being provided intermediate its end with pockets or receiving spaces for rollers or rockers that support the body on the under-frame, the receiving spaces being of sufficient depth so 25 that the center of gravity of the tilting body, when empty, will be below the points where the body is supported on said rollers or rockers.

9. A dumping car or other vehicle of the 30 class described having in combination with the main under-frame thereof a tilting body that is provided thereupon with transversely extending tracks, rollers which are mounted upon tracks on the under-frame and upon 35 which rollers the tracks upon the tilting body are supported whereby the body can be moved toward either side of the car, said tracks being provided with projecting portions or teeth which enter notched portions 40 in the rollers, the construction and arrangement of said tracks and rollers being such that when the car body is moved toward the side of the car the rollers will be moved toward the same side of the car.

45 10. In a car or other vehicle of the class described an under-frame, rollers thereupon and arranged in pairs so that each pair can move transversely relative to the under-

frame, a tilting body resting on said rollers, and mechanism for shifting the body horizontally to either side until the body starts to tilt, and which mechanism is constructed so as to permit the body to tilt, the construction of the rollers and the body being such that the body travels substantially 50 twice as far as the center lines of the rollers until the body starts to tilt, from which time the rollers on the side to which the body is tilted move with the body and serve as 55 rockers.

11. A car of the class described comprising a longitudinally extending underframe having thereon horizontally transversely extending tracks, rollers on said tracks and movable along the same, a tilting body having track members which extend horizontally and transversely, when the body is in central or load carrying position, and which track members rest upon said rollers whereby the body is supported by means of 60 the rollers, said body track members being above the center of gravity of the body 65 when empty.

12. A dumping car or other vehicle of the class described having in combination with 70 the main underframe thereof a tilting body that is provided with transversely extending tracks, said tracks being located above the center of gravity of the body, the rollers mounted upon tracks which are upon the underframe, upon which rollers said tracks upon the body members are supported whereby the body can be moved to either side of the car, the construction being such that when the body is moved toward a side 75 of the car the rollers will be moved along the tracks on the underframe and the tracks on the body will be moved longitudinally relative to the rollers.

This specification signed and witnessed 80 this 24th day of November, A. D. 1914.

HENRY FORT FLOWERS.
